US0D1071994S

(12) **United States Design Patent** (10) **Patent No.:** **US D1,071,994 S**
(45) **Date of Patent:** **** Apr. 22, 2025**

(54) **INTAKE MANIFOLD**

(71) Applicant: **Holley Performance Products, Inc.**,
Bowling Green, KY (US)

(72) Inventors: **Coy Hudnall**, Bowling Green, KY
(US); **Kevin Tracy**, Port Charlotte, FL
(US)

(73) Assignee: **Holley Performance Products, Inc.**,
Bowling Green, KY (US)

(**) Term: **15 Years**

(21) Appl. No.: **29/860,947**

(22) Filed: **Nov. 23, 2022**

(51) LOC (15) Cl. **15-01**

(52) U.S. Cl.

USPC **D15/5**

(58) **Field of Classification Search**

USPC D15/1-5; D12/194

CPC F02M 31/087; F02M 1/00; F02M
2700/4392; F02M 35/104; F02M 35/108;
F02M 35/116; F02M 35/1085

See application file for complete search history.

(57) **CLAIM**

The ornamental design for an intake manifold as shown and described.

DESCRIPTION

FIG. 1 is a first perspective view of a design of an intake manifold;

FIG. 2 is a second perspective view of the design of FIG. 1;

FIG. 3 is a front view of the design of FIG. 1;

FIG. 4 is a rear view of the design of FIG. 1;

FIG. 5 is a first side view of the design of FIG. 1;

FIG. 6 is a second side view of the design of FIG. 1;

FIG. 7 is a top view of the design of FIG. 1; and,

FIG. 8 is a bottom view of the design of FIG. 1.

The broken lines shown in the drawings are included for the purpose of illustrating the unclaimed boundary and/or unclaimed portions of the intake manifold. The broken lines form no part of the claimed design.

1 Claim, 8 Drawing Sheets
